(57) **CLAIM**

The ornamental design for a heart shaped glass holder, as
shown and described.

DESCRIPTION

FIG. 1 is a perspective view of a heart shaped glass holder
having two through holes.

FIG. 2 is a perspective view of the heart shaped glass holder
and two glasses.

FIG. 3 is a side view of the heart shaped glass holder and a
glass.

FIG. 4 is a top view of the heart shaped glass holder and two
glasses; and,

FIG. 5 is a bottom view of the heart shaped glass holder.
The broken lines are for illustrative purposes only and form
no part of the claimed design.
